CONTAINER

William H. Inman, Newark, N. Y., assignor to
 Bloomer Bros. Company, Newark, N. Y., a corporation of New York

Application April 1, 1933, Serial No. 663,990

2 Claims. (Cl. 229—39)

This invention deals with a container or carton. An object of the invention is to provide a container of non-circular shape with rounded corners, which may be formed comparatively inexpensively from sheet material such as cardboard or the like.

Another object is to provide such a container so designed and constructed that it may be knocked down into substantially flat condition, 10 or erected in normal condition for use, as desired.

Another object is the provision of such a container which may be formed economically from a relatively small quantity of sheet material, and yet which is sufficiently strong and rigid for the 15 purposes for which it is intended.

A still further object is the provision of such a container in which the closure parts or ends assist in holding the container in erected position, and in which the closure parts or ends are 20 securely fastened and held in place.

To these and other ends the invention resides in certain improvements and combinations of parts, all as will be hereinafter more fully described, the novel features being pointed out in 25 the claims at the end of the specification.

In the drawing:

Fig. 1 is an end view of a container constructed in accordance with a preferred embodiment of the invention;

30 Fig. 2 is a side view of the same;

Fig. 3 is a partial side view on a slightly larger scale than Fig. 2, illustrating one of the locking tabs in upstanding position ready to be folded over and interlocked with a side of the container;

35 Fig. 4 is a sectional view through one end of the container taken substantially on the line 4—4 of Fig. 1;

Fig. 5 is a section substantially on the line 5—5 of Fig. 1, and

40 Fig. 6 is a plan of a blank of sheet material cut and scored so that it may be conveniently formed into a container of the shape shown in Figs. 1 and 2.

The same reference numerals throughout the 45 several views indicate the same parts.

The container of the present invention may have any desired number of sides, three or four sides preferably being employed. The container illustrated in the drawing as a preferred embodiment of the invention has three sides and is of generally triangular shape as best illustrated in Fig. 1, having sides indicated by the numerals 10 and rounded corners 11 between the sides, these corners being rounded on a material or appreciable radius, as shown, so that the container

presents no sharp corners. Preferably the body is formed from a single piece or blank of sheet material such as that indicated by the numeral 10a in Fig. 6. The main body portion of such a blank may be formed into a loop with its opposite edges overlapping and secured to each other by glue or the like. After the blank has thus been formed into a loop, it may be shaped to the desired shape and held in this shape by means of the closure parts or ends to be described later, 10 or it may be knocked down into a substantially flat condition by folding the looped body along the two score lines 12 and 13, which are so placed that the length of material between the two score lines is substantially the same on one side of a 15 plane passing through the two lines as on the other side of such a plane.

Closure parts or ends are provided, preferably set inwardly from the end edges of the body so that the edges of the ends engage the interior 20 surfaces of the body and assist in holding the body in the desired cross sectional shape. The two ends of the carton may be of similar construction, each comprising preferably only a single thickness of sheet material, indicated at 15. 25

When the closure parts 15 are designed to occupy a position set slightly inwardly from the ends of the carton, as shown in Figs. 4 and 5, then the carton body preferably is provided with a score line 16 extending around the body in the 30 plane of each end, the score line being formed to provide a slight depression on the interior of the body so that the edges of the end 15 may engage in this score line as shown in Fig. 5, thus assisting in retaining the member 15 properly in 35 place in its intended plane.

Additional means are preferably also provided for holding the ends or closure parts, and such additional means preferably connects each end to each of the sides of the carton. For instance, the 40 end parts 15 are preferably formed integrally from the same piece of sheet material 10a which forms the carton body, one side of each end part being connected to one side of the carton body by means of a strip or neck 17 which, in effect, forms 45 a hinge for the end part. When the closure is in normal closed position, the strip 17 extends inwardly from the edge of one side 10 of the body to an edge of the end member 15. The other sides of the end members have tongues preferably 50 formed integrally from the same sheet material, each tongue having, for example, a portion 18 adapted to extend outwardly from the end member to the edge of the associated side of the carton, the tongue then being bent along the score

line 19 so as to extend around the edge and having a portion 20 to run along the exterior of the side of the container and adapted to be interlocked therewith by any suitable means. For example, the side of the container may have a circumferential slit 21 intersected by two short longitudinal slits 22, the three slits together forming an opening through which the interlocking end 23 of the tongue may be inserted as shown in Fig. 4, and which is adapted to retain this interlocking end of the tongue until it is forcibly removed, in a manner well understood by those skilled in the art. It is to be noted also that the tongues 17 and 18—20 serve to some extent to hold the sides of the container against the peripheries of the ends 15 and tend to prevent the sides from bulging outwardly between the rounded corners.

From the foregoing description, it will be readily apparent that there has been provided a simple carton or container having materially rounded edges, which container has ends which strengthen the container and assist in retaining it in the desired cross sectional shape. The container may be quickly knocked down to a flat condition even after the ends of the blank have been pasted together, and may be quickly erected when desired. The entire container including the ends and the interlocking means for holding the ends in position, may be and preferably is formed from a single piece of suitable fibrous sheet material such as card stock, cardboard, or the like.

While one embodiment of the invention has been disclosed, it is to be understood that the inventive idea may be carried out in a number of ways. This application is therefore not to be limited to the precise details described, but is intended to cover all variations and modifications thereof falling within the spirit of the invention or the scope of the appended claims.

I claim:

1. A container of fibrous sheet material formed to provide a body portion of generally triangular cross section with rounded corners, slits in certain sides of said body portion, a closure member extending across the interior of said body portion in a plane offset inwardly from the end edges of said sides, and tongues secured to said closure member and extending thence around the end edges of certain of said sides and externally along said sides to said slits and being interlocked with said slits. 10

2. A container of fibrous sheet material formed to provide a body portion having a plurality of sides and rounded corners, said body portion being capable of being knocked down to a substantially flat condition, a closure member capable of being extended across said body portion inwardly from an end thereof, when said body portion is erected, retaining members secured to said closure member to extend externally along certain of said sides, and means for interlocking said retaining members with said sides. 20 25 30
